TOOLHOLDER

Henry Sundstrom, Dearborn, Mich.

Application September 21, 1943, Serial No. 503,251

3 Claims. (Cl. 29—97)

The present invention relates to new and useful improvements in tool holders for vertical turret lathes and other turning machines, and has for its primary object to provide, in a manner as hereinafter set forth, a device of this character comprising a novel construction, combination and arrangement, whereby the spacing and angle of the tools may be expeditiously adjusted as desired.

Other objects of the invention are to provide a tool holder of the aforementioned character which will be comparatively simple in construction, strong, durable, highly efficient and reliable in use, compact, and which may be manufactured at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is a view in side elevation of a tool holder constructed in accordance with the present invention.

Figure 2 is a view in front elevation thereof.

Figure 3 is a rear elevational view.

Figure 4 is a view principally in vertical section, taken substantially on the line 4—4 of Figure 2.

Figure 5 is a detail view in vertical section through one of the adjustable and removable chucks, showing a tool secured therein.

Figure 6 is a perspective view of one of the chucks.

Figure 7 is a perspective view of one of the spacers.

Figure 8 is a perspective view of one of the angle wedges.

Referring now to the drawings in detail, it will be seen that the embodiment of the invention which has been illustrated comprises a metallic block 1 of suitable dimensions. Rising from the block 1 is an integral shank 2 for mounting the holder on the machine.

The block 1 has formed in its forward portion a recess or chamber 3 which is open at the front and bottom of said block. The block 1 is further provided, in its rear portion, with a transverse slot 4 which communicates throughout its length with the chamber 3, said slot including a widened or enlarged outer portion 5.

The chamber 3 is for the reception of a plurality of chucks 6 in the form of rectangular

metallic blocks having vertical passages 7 therein extending from top to bottom thereof for the reception of tools 8. Allen set screws 9 are threadedly mounted in openings provided therefor in the front portions of the chucks 6 for releasably securing the tools 8 in position. If desired, the chucks 6 may comprise two or more of the passages 7 to accommodate a plurality of the tools 8. The chucks 6 are further provided, in their upper, back portions, with threaded openings 10 which communicate with the passages 7. The openings 10 are for the reception of screws 11 in the slots 4 for adjustably and removably securing the chucks 6 in position in the block 1. The heads 12 of the securing screws 11 are engaged with the shoulders 13 which are provided in the block 1 by the enlarged or widened portion 5 of the slot 4.

The chamber 3 also accommodates metallic spacers 14 of suitable thickness for the chucks 6. Mounted on the front of the block 1 and extending transversely across the chamber 3 for retaining the members therein is a metallic supporting bar or brace 15. Allen screws 16 secure the bar 15, the block 1 being tapped to accommodate said screws.

The chamber 3 also accommodates wedges 16 of suitable metal which are adapted to be mounted between the chucks 6 when it is desired to mount the tools 8 at an angle, as illustrated to advantage in Figures 2 and 3 of the drawings. Projecting forwardly from the small end portions of the wedges 16 are integral lugs or the like 17 which are engageable with the bar 15 for positively preventing said wedges from slipping in the direction of their large ends. Allen set screws 18 are threadedly mounted in the end portions of the block 1 for adjusting the members 6, 14 and 16 and for securing said members in position.

It is thought that the manner of using the holder will be readily apparent from a consideration of the foregoing. Briefly, the tools 8 are mounted in the chucks 6 and secured by the screws 9. If desired, this may be done before the chucks 6 are mounted in the block 1. With the screws 11 loose, the chucks 6 may be readily adjusted to any desired position in the chamber 3. The members 14 and 16 are mounted in the chamber 3 between the desired chucks 6 and the bar 15 is secured in position. The adjustment of the assembly is then secured by tightening the screws 18 and 11. Of course, any other suitable

procedure may be followed when assembling the device.

It is believed that the many advantages of a tool holder constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. A tool holder of the character described comprising a block having a chamber therein open at the front and bottom of said block, the block further having a slot therein communicating with the chamber, a plurality of chucks for the reception of tools, removably and adjustably mounted in the chamber, screws adjustable in the slot and connected to the chucks for securing said chucks in the chamber, a retaining bar for the chucks mounted on the front of the block and extending across the chamber, and means for adjusting the chucks in the chamber.

2. A tool holder of the character described comprising a block having a chamber therein, a plurality of chucks, for the reception of tools, removably and adjustably mounted in the chamber, a bar mounted on the block and extending across the chamber, wedges in the chamber between the chucks for retaining the adjacent tools

at an angle relative to each other, and lugs on the wedges engaged with the bar for retaining said wedges against longitudinal movement.

3. A tool holder of the character described comprising a metallic block having a chamber therein open at the front and bottom of the block, said block further having a slot therein communicating with the chamber, an attaching shank for the block integral therewith, a bar mounted on the front of the block and extending across the chamber, a plurality of chucks adjustably and removably mounted in the chamber, said chucks having passages therein for the reception of tools and further having threaded openings therein communicating with the passages; means for securing the tools in the passages, screws adjustable in the slot and threadedly engaged in the openings for securing the chucks in the chamber, spacers for the chucks removably mounted in the chamber, removable wedges in the chamber between certain of the chucks and the spacers for retaining the tools at an angle relative to each other, integral lugs projecting forwardly from the small end portions of the wedges and engaged with the bar for retaining said wedges against longitudinal movement, and set screws threadedly mounted in the block for securing the chucks, the spacers and the wedges in adjusted position in the chamber.

HENRY SUNDSTROM.
